UNITED STATES PATENT OFFICE.

JOHN H. WOLF, OF MOUNT HOORB, WISCONSIN.

REMOVABLE HORSESHOE-CALK.

1,145,956.

Specification of Letters Patent.

Patented July 13, 1915.

Application filed March 19, 1914. Serial No. 825,880.

To all whom it may concern:

Be it known that I, JOHN H. WOLF, a citizen of the United States, residing at Mount Horeb, in the county of Dane and State of Wisconsin, have invented a new and useful Removable Horseshoe-Calk, of which the following is a specification.

The device forming the subject matter of this application is a horseshoe, and the primary object of the invention is to improve the shoe by enhancing the grip thereof upon the ground.

Specifically, the invention aims to provide novel means for assembling the strip tread detachably with the shoe, and, with this end in view, the invention contemplates the provision of a novel form of calk adapted to hold the strip tread, novel means being provided for assembling the calk with the shoe.

It is within the scope of the invention to improve generally and to enhance the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing:—Figure 1 shows in bottom plan, a horseshoe constructed in accordance with the present invention; Fig. 2 is a side elevation of the structure shown in Fig. 1; Fig. 3 is a rear end elevation of the shoe; Fig. 4 is a transverse section taken approximately on the line 4—4 of Fig. 2; Fig. 5 is a side elevation of the calk detached from the shoe; Fig. 6 is a bottom plan of the calk detached from the shoe; Fig. 7 is an end elevation of the detached calk.

In the accompanying drawings, the numeral 1 indicates a horseshoe of standard construction and provided with the usual nail holes 2. Adjacent the toe of the shoe 1 and adjacent the heel thereof, openings 3 are formed, as shown in Fig. 4, these openings preferably but not necessarily extending entirely through the shoe.

The invention contemplates the use of one or more toe calks 4 and a pair of heel calks

5. Since the calks 4 and 5 are of identical construction, but one of them need be described in detail. Each calk is of trough-shape and is open at both ends, the same comprising a top 6 and downwardly extended, converging side walls 7. A stud 8 upstands from the top 6 of the calk and preferably is of tapered or frusto-conical construction. There may be any number of these studs 8 upon each calk, the openings 3 which receive the studs being decreased or increased accordingly in number. The openings 3 are originally bored or formed cylindrically, but when the tapered or wedge-shaped studs 8 are driven into the openings 3, the openings will be distended, as indicated in Fig. 4, and thus the calk will be held securely to the shoe 1.

Projecting downwardly from the top 6 of the calk and located between the side walls 7 are prongs 9. Any number of prongs may be provided upon each calk. The prongs 9 are of tapered form and are widest adjacent the top 6, that is, they are widest adjacent the place of greatest separation of the side walls 7. At their lower edges, the side walls 7 are provided with inwardly extending, approaching, sharpened lips 10 which may be formed by battering over the inner edges of the side walls 7 slightly.

In the present embodiment of the invention there is employed a continuous strip tread 11 substantially coextensive in lineal extent with the shoe 1. The tread 11 is flexible, and may be in the form of a piece of rope. The tread 11 is wedged between the side walls 7 and is impaled upon the prongs 9. Because the prongs 9 are widest adjacent the top plate 6, the tread is expanded by the prongs 9 between the downwardly converging side walls 7 of the calk. By this construction, the tread 11 is held in place, and the hold of the calk upon the tread is further enhanced by the provision of the lips 10 which may extend beneath the tread, or bite into the tread slightly if the tread is of sufficient diameter.

It is to be observed that the calks 4 and 5 are spaced apart. Therefore, the full compressive effort is applied to the tread, between the calks 4 and 5 and thus the grip of the shoe upon the ground is promoted. Further, because the tread 11 is free between the calks 4 and 5, the tread may be flexed laterally so as to uncover one or more of

the nail holes 2. A loose nail, therefore, may be replaced, without removing the entire auxiliary gripping structure, comprising the calks 4 and 5 and the tread 11, from 5 the shoe proper 1.

It is to be observed that any standard form of horseshoe may be adapted for use in the present invention by merely boring or forming otherwise the openings 3 in the 10 shoe. The calks 4 and 5 may be driven to place, the studs 8 being wedged in the openings 3. Although the studs 8 engage wedge-wise in the openings 3 with sufficient hold to maintain the calks 4 and 5 on the shoe 15 1. when the latter is in use, the calks, by the application of a sufficient force may be pried loose from the shoe. The taper given to the studs 8 will depend upon the taste of the user and probably the taper has been exaggerated slightly in the drawings, in order 20 that this feature may be made manifest by a mere inspection of the drawings.

It is to be observed that each calk 5 is 25 provided adjacent its rear end with a single tapered stud 8, these studs being adapted to be received in the openings 3 of the shoe. The tread 11 is assembled with the toe and heel calks, the smaller, upper ends of the 30 studs 8 being seated loosely in the openings 3. Then, the forward ends of the calks 5 may be shifted transversely of the shoe for a double purpose: first, in order that the intermediate portion of the tread 11 may be 35 so positioned that it will cover the nail holes 2; and secondly, in order that the tread 11 may be positioned close enough to the outer edge of the shoe so that the tread, when desired, may be sprung inwardly to 40 uncover the nail holes 2. After the forward ends of the calks 5 have thus been adjusted, the calks are driven to place, so that the

studs 8 become wedged in the openings 3 as hereinbefore stated, the calks 5 and consequently the intermediate portion of the tread being held in adjusted positions with respect 45 to the nail holes 2.

Having thus described the invention, what is claimed is:—

A device of the class described comprising a shoe provided upon its sides with nail holes 50 and having openings adjacent its heels; a trough-shaped calk assembled with the toe of the shoe; trough-shaped heel calks spaced from the toe calk; and a tread lodged in all of the calks and covering the nail holes, the 55 tread being laterally flexible between the toe and heel calks independently of the toe and heel calks to uncover the nail holes; the heel calks being provided adjacent their rear ends, each, with a single tapered stud 60 which, coöperating initially with one opening in the shoe, permits the forward end of the heel calk to be adjusted transversely of the shoe, thereby adjusting the tread transversely of the shoe, to the end that the tread 65 may at once be positioned to cover the nail holes and be so positioned with respect to the nail holes that the tread may be flexed laterally to uncover the nail holes, the stud being adapted to be finally wedged in the opening in the shoe, thereby to hold the heel calk and the intermediate portions of the tread in adjusted position with respect to the nail holes.

In testimony that I claim the foregoing 70 as my own, I have hereto affixed my signature in the presence of two witnesses.

JOHN H. WOLF.
